MANUFACTURE OF AN IMPROVED TALL OIL

Harold R. Murdock, Canton, N. C., assignor to The Champion Paper and Fibre Company, Canton, N. C., a corporation of Ohio

No Drawing. Application August 11, 1938,
Serial No. 224,414

9 Claims. (Cl. 260—97.5)

This invention relates to a process of refining crude tall oil. It is well known in the wood pulping industry that when the black liquor obtained from the pulping of coniferous wood by the sulphate process is evaporated, a scum, commonly known as tall oil soap, separates and floats upon the surface of the black liquor. This scum is not present on the liquors as they are obtained before the evaporation step, but is produced, probably by a salting out effect, as the liquor becomes concentrated. In present practice the scum of tall oil soap is skimmed off of the evaporated black liquor and either used as such to produce crude sodium salts of tall oil or more frequently the scum is treated to form crude tall oil. The crude tall oil soap is usually treated with dilute solutions of sulphuric acid or sodium acid sulphate to liberate this crude tall oil. In order to facilitate the separation of the mixture into two layers, the use of sodium sulphate with the acid to increase the density of the water layer is common practice. After the acid has reacted the crude tall oil is the upper layer and can be separated from the lower aqueous sodium sulphate layer by decantation or any other suitable means commonly used in the chemical industries.

Crude tall oil, prepared in the above manner, is of limited usefulness in industrial application. It possesses the usual foul odor typical of sulphate black liquors; it is of dark brown color; and an even greater objection is its tendency to crystallize partially, producing a thick viscous paste difficult to pump and difficult to remove from shipping containers. This tendency to crystallize varies depending upon the history of the wood from which it originates. Consequently, crude tall oil lacks uniformity in chemical composition and physical characteristics.

It is the purpose of this invention to provide a simple economical process by which tall oil can be made more uniform in its physical appearance with an improved odor and color as compared to the crude tall oil now found in commerce. The improved tall oil produced in accordance with my process to be described hereinafter has been found to be free of those crystalline suspensions which occur in the crude product and consequently is a smooth uniform oily product. It is capable of standing in storage indefinitely without crystallization.

To understand the advantages offered by this invention it is essential to appreciate the lack of uniformity found in tall oil resulting from the variations in the kind of wood used in the proc-

ess, and more particularly from variations in the history of this wood. When southern pine is pulped by the sulphate process promptly after it is cut green, it yields a tall oil different from that produced when the logs are pulped after they have been cut and exposed to the air for months. When a pine tree is cut it exudes resinous matter in an attempt to seal the wound. This necessarily places a large portion of the resinous content of the wood in contact with the air, and after long exposure the air penetrates the wood and oxidizes some of the constituents of the resinous exudation to chemical compounds which are not present when the tree is freshly cut and promptly processed. Inasmuch as the chemical constituents of the exudation are complex and of many types, the chemical changes by oxidation are not entirely understood.

Experience has proved also that in the case of wood cut in the spring of the year the ratio of fatty acids to the resin acids is considerably higher than in the tall oil obtained by pulping wood which has been cut in the winter when the sap is out of the tree. Because of these variations in the wood used, crude tall oil is of variable composition. When the fatty acid content is relatively high the crude tall oil is easy-flowing and contains fewer crystals than the heavier, darker, crude tall oil obtained from old wood. These variations have retarded the industrial application of crude tall oil.

Experimentation has shown that abietic acid oxidizes to hydroxyabietic acid under mild oxidizing conditions. This can occur to a certain extent when the coniferous wood stands exposed to air after being cut. Hydroxyabietic acid is less soluble in fatty acid than is abietic and consequently it tends to crystallize out of crude tall oil. These crystals probably act as a nuclei for the crystal growth of other resinous products present in the crude tall oil. In any event hydroxyabietic acid is believed to account for the partial solidification of crude tall oil due to crystal formation.

Confirmation of this condition is found by experiment when the crude tall oil obtained from pulping freshly cut pine wood is agitated by air at slightly elevated temperatures. Such treated crude tall oil shows more crystal formation than does the untreated product.

It is one of the objects of this invention to eliminate the presence of hydroxyabietic acid and other oxidized analogous or related compounds and derivatives by chemically processing the crude tall oil. I heat the crude tall oil, at

first rather slowly, to drive off water which is not chemically bound and some low-boiling odorous materials. I then continue the heating progressively until a maximum temperature of 5 250-350° C. has been attained. I usually prefer to maintain a temperature of at least about 10 300° for at least an hour in order that the chemical reactions which occur during this heating 15 may be substantially completed. Care is taken 10 that the tall oil does not come in contact with air during the heating operation and that the 15 vaporized products are removed. After the mechanically held water has been driven away the 20 volatile products coming from the heated tall oil 15 show an increasing volume of vapor as the temperature rises. This vapor is substantially all water, formed by pyrolysis, and also contains sulphur bodies coming from the lignin and other sulphur compounds always present in crude 25 tall oil as impurities.

A variety of procedures may be employed in the heating operation as will be apparent to one skilled in the art. I have found it advantageous to heat the tall oil in two stages, first to a temperature in the neighborhood of 100° C. to remove free water and readily vaporizable constituents and then to about 325° C. to effect the chemical changes described. Each heating stage advantageously is accompanied by a flowing 25 of the heated material in a thin layer over a splash plate or the like to facilitate the removal of volatile constituents. In some instances I have found it desirable to maintain a temperature of 325° C. for about 3 hours.

35 If the tall oil is dry at the start the loss of tall oil as a result of the heat treatment generally does not exceed 5%.

The heating of the crude tall oil results in a product which will be found to have changed 40 chemically and physically in characteristics. In the first place, its color after cooling will be found to be changed from a yellowish-brown to an iridescent green, a color similar to that observed in petroleum lubricating oils. Also the 45 odor is decidedly improved because of the substantial loss of sulphur compounds found in crude tall oil. The derived odor is suggestive of a burnt or charred organic substance. This odor, I believe, is due to the charring of small 50 traces of lignin usually present in tall oil. Although it is not necessary in carrying out my process, I may remove this burnt odor by treatment with hydrogen in the presence of a catalyst in the usual manner common in hydrogenation 55 of oils. While one may continue the treatment with sufficient hydrogen to hydrogenate the fatty and resin acids, as well as the odorous materials, this is not essential as the odorous materials appear to be converted to non-odorous products rapidly by hydrogen treatment. I also appreciate the possibility of removing these odorous materials by many of the known methods used in the art, such as superheated steam, activated carbon, etc. Filtration for the removal of solid 60 matter is not necessary. The constituents which normally result in the deposition of solids from crude tall oil apparently are destroyed or rendered more soluble or removed by distillation during the heating and vaporizing treatment 65 described.

70 Probably the major change which occurs in crude tall oil when processed as described is the lowering of the resin acid content of the oil and the simultaneous substantial increase in the unsaponifiable content in the oil. Merely as a mat-

ter of possible explanation I offer the following theory to account for this chemical change during the process. Hydroxyabietic acid has been found to be unstable at temperatures of 200° C. and higher. It is believed that the oxidized products in crude tall oil, among which is probably hydroxyabietic acid, become dehydrated during the heating process. This produces anhydrohydroxyabietic acids and possibly polymerized or isomerized colophonic acids. Evidence 10 also indicates that some of the carboxyl groups of these resin type acids are destroyed in the heating process. Any one of the above conditions would account for the lower acid number found on the heated product, as well as the increased unsaponifiable value. It appears also that abietic acid if present probably is converted to the more stable pyroabietic acid. 15

The following table shows the changes produced by the above described heating and vaporizing treatment. 20

	Before	After
Acid number.....	155	132 25
Saponification number.....	170	145
Density.....	0.9-1.0	1.009
Fatty acids.....	per cent 25.75	27.5
Resin acids.....	do 65	57
Unsaponifiables.....	do 8.06	13.9
Iodine number.....	135	112
Ash.....	per cent 0.12	0.15 30

The improved odor, together with the relatively increased percentage of fatty acids, has rendered the product suitable for use in the manufacture of such commercial articles as soaps, printing inks, 35 greases, rubber compounds, etc., where the crude tall oil has never been found adaptable.

After deodorizing with hydrogen as described above the product has a definitely sweet fatty odor far more desirable than the foul odor of the 40 crude tall oil.

The product is characterized physically by its improved odor compared to tall oil and by its freedom from any tendency to crystallize on standing. Chemically it appears to be most distinctly characterized by its freedom from hydroxyabietic acid. 45

I claim:

1. Process for the production of refined tall oil which is a smooth, uniform, oily liquid capable of prolonged standing without crystallization which 50 consists in raising the temperature of crude tall oil from coniferous wood to a maximum between about 250° C. and about 350° C., said heating operation serving to vaporize and expel mechanically associated water, water produced by pyrolysis, low 55 boiling odorous materials and sulfur compounds, the loss by vaporization from tall oil which is dry at the beginning of the heating operation generally not exceeding 5%, and separating the residual liquid from the vaporized materials. 60

2. Process as defined in claim 1 in which the crude tall oil is first heated slowly to drive off mechanically associated water and some low boiling 65 odorous materials and then is heated progressively to a maximum temperature of 250°-350° C. and the heating is continued at said temperature for a time sufficient to permit completion of chemical reactions occurring at said temperature. 70

3. Process as defined in claim 1 in which the heating at said maximum temperature is carried out at least about 300° C. for at least about 1 hour. 75

4. Process as defined in claim 1 in which the heating at said maximum temperature is at about 325° C. for about 3 hours. 75

5. Process as defined in claim 1 in which the tall oil is flowed in a thin layer during said heating operation.
6. Process as defined in claim 1 in which air is excluded from contact with the tall oil during the heating operation.
7. As a new product refined tall oil from coniferous wood, being a smooth, uniform, oily liquid having an iridescent green color and an improved odor compared with that of crude tall oil and capable of prolonged standing without crystallization, said refined tall oil amounting to at least

about 95% by weight of the weight of the dry crude tall oil and containing the organic products of pyrolysis of the hydroxy abietic acid content of the crude tall oil.

8. Refined tall oil as defined in claim 7 having, as compared with crude tall oil lower acid number, saponification number, resin acid content and iodine number and higher fatty acid content and unsaponifiable content.

9. Refined tall oil as defined in claim 7 being substantially free of hydroxy abietic acid.

HAROLD R. MURDOCK.
